DEVICE FOR RECOIL CONTROL

Robert H. S. Hughes, Baltimore, Md., assignor of
one-half to Milton Roberts, Baltimore, Md.

Application April 25, 1938, Serial No. 204,175

4 Claims. (Cl. 39—14)

This invention relates to recoil control mechanism for guns and particularly to means associated with said mechanism for reducing the blast, flash and smoke which usually result from the discharge of firearms.

In the accompanying drawings:

Figure 1 is a central longitudinal section through one of my control devices, showing the same attached to the forward end of a gun barrel, the latter being also shown in longitudinal central section.

Figure 2 is a front end view of the device shown in Figure 1.

Figure 3 is a section on the line 3—3 of Figure 1;

Figure 4 is a longitudinal section through a modified form of device, showing the same attached to the front end of a gun barrel;

Figure 5 is a similar view of another modification, the section being taken on the line 5—5 of Figure 6;

Figure 6 is a front end view of the device shown in Figure 5;

Figure 7 is a section on the line 7—7 of Figure 5;

Figure 8 is a longitudinal central section through a long form of condenser shield, the recoil device being shown in outline.

Referring to Figures 1 to 3 inclusive of the drawings, 1 indicates a gun barrel having the usual grooves 3 and lands 4. Upon the muzzle end 2 of the barrel is shown an adapter 5 having an outwardly extending flange 6 at its end and having an inwardly extending shoulder 6^a, which rests against the end of the gun barrel. A sleeve 7 extends forwardly from the shoulder, this sleeve being concentric with the gun barrel and the interior of the sleeve having substantially the same internal diameter as the bore of the gun. A metal body 8 is threaded on to the adapter and is held against rotation by a set screw 9. The body 8 has a cylindrical combustion chamber 10 into which the sleeve 7 projects, and at its forward end the body has a seal port 15 in line with the bore of the sleeve and with the bore of the gun barrel when the device is mounted on a gun. An annular shoulder 12 extends from the inner end of the seal port to the side wall of the chamber and a plurality of discharge ports 11 extend rearwardly and outwardly from the forward part of the chamber adjacent said internal shoulder through an external shoulder 16. Baffle ports 17, in the form of arcuate slots, extend through the side wall of the chamber at the rear of the discharge ports

11, so that gases issuing through the baffle ports will intercept the gases passing from the discharge ports.

A metal shield c is mounted on the recoil device and surrounds it and this shield forms a condenser for the products of combustion issuing from the ports of the recoil device. As shown, this shield comprises a cylindrical part 25 projecting in advance of the seal port 15 and threaded on to the part 14 through which the seal port extends, as shown at 24. From the part 25 the shield flares outwardly and rearwardly as shown at 18 to a rearwardly extending cylindrical portion 19 which terminates in a bell mouth 20. The body 8 of the recoil device has a sloping surface 22 against which a sloping surface 21 on the inner side of the shield bears, so that when the shield is threaded on to the recoil device it will be held firmly in place. The part 19 of the shield surrounds the recoil ports and baffle ports 11 and is spaced from them and the part 25 is concentric with the seal port and is spaced from it and extends in advance of it.

In the operation of the device shown in Figures 1 to 3, when the gun is fired the bullet passes through the sleeve 7, the chamber 10, seal port 15 and condenser 25. The products issuing from the gun barrel and entering the chamber 10, following the bullet, are in all stages of combustion, some still passing from the solid state through a plastic or liquid state to the gaseous state, and when the bullet is in the seal port an extremely high pressure develops in the chamber. The gases and still burning products of combustion are ejected through the discharge ports 11 and baffle ports 17 against the part 19 of the condenser. Without the condenser the discharge of these products through the ports 11 against the atmosphere, by reaction against the shoulder 13, would largely eliminate recoil, and the discharge through the baffle ports, by intercepting the discharge through the ports 11, would largely eliminate blast against the operator of the firearm. When the condenser c is applied to the device, as shown in Figure 1, the amount of recoil elimination will be reduced somewhat but so will the blast, flash and smoke be largely eliminated because the still burning products of combustion, partly in liquid or plastic state, will be driven against the condenser wall and condensed thereon. In the same way, the still burning products of combustion issuing from the seal port as the bullet leaves said port, will expand outwardly against the forward condenser 25 and

be condensed thereon, thereby reducing the flash, blast and smoke.

In Figure 4 the parts are the same as in Figure 1 and similarly numbered, except that the part 5 14 has a tubular extension 32 extending forward in line with the seal port as far as the end of the condenser 25, and this extension has a plurality of narrow slots 33 in its wall, which the bullet must pass after leaving the seal port, and 10 through these slots the products of combustion will be driven against the wall of the part 25 and any products in the fluid or plastic state will be condensed, thus reducing the smoke, blast and flash.

15 In Figure 5 the condenser c' has the cylindrical rear portion 40 and tapering forward portion 41, like the parts 19 and 18 in Figure 1, but it extends forwardly only as far as the end of the seal port. The body 8 of the recoil device 20 has a tubular extension 15^a which forms the seal port 16, and the condenser c' has suitably secured within its forward end a spider 2, the arms 35, 36 and 37 of which are welded or otherwise secured within the forward end of the 25 tapering part 41 of the condenser. The spider has a central opening adapted to receive the tubular part 15^a and the spider is threaded onto said part as indicated at 42. The inner wall of the condenser rests against ribs 43, 43^a and 43^b 30 on the body (Figure 7) which hold the condenser in position concentric with the axis of the chamber and seal port. In this form of device, the spaces surrounded by the front and rear portions of the condenser are in communication 35 with one another and with the atmosphere. The operation is substantially the same as that described in connection with Figure 1.

In Figure 8 I have shown a modification in which the condenser element c² has a cylindrical 40 rear portion 40 and tapering portion 41, the same as in Figure 5, but there is also a long forward extension 50. This condenser element can be applied to a recoil device as in Figure 5, said device being indicated in dotted lines in 45 Figure 8. In this case products of combustion issuing from the various ports will contact the condenser element throughout its length and any still burning plastic particles will condense thereon, thus reducing the smoke, blast and flash.

50 I claim:

1. A recoil controlling device comprising a metal body having a combustion chamber therein, said body having at the forward end of the chamber a seal port and a reaction shoulder surrounding the inner end of said port and 55 extending to the side wall of the chamber and having discharge ports extending outwardly and rearwardly from said shoulder and baffle ports in its side wall at the rear of the discharge ports, and also having means at its rear end for connecting the device to a gun barrel with the bore 60

of the barrel in alignment with the seal port, and a condenser comprising a metal shield secured to the forward part of the body and extending rearwardly and open at its rear end, said shield surrounding the discharge ports and baffle ports and spaced therefrom.

2. A recoil controlling device comprising a metal body having a combustion chamber therein, said body having at its forward end a seal port and a reaction shoulder surrounding the inner end of said port, and having discharge ports extending outwardly and rearwardly from said shoulder and baffle ports in its side wall at the rear of the discharge ports, and also having means at its rear end for connecting the device to a gun barrel with the bore of the barrel in alignment with the seal port, and a condenser comprising a metal shield secured to the forward part of the body and having a part extending rearwardly and open at its rear end, said part 10 surrounding the discharge ports and baffle ports, and a part projecting forwardly beyond the seal port and having its forward end open.

3. A recoil controlling device comprising a metal body having a combustion chamber therein, said body having at its forward end a seal port and a reaction shoulder surrounding the inner end of said port, and having discharge ports extending outwardly and rearwardly from said shoulder and baffle ports in its side wall 20 at the rear of the discharge ports, and also having means at its rear end for connecting the device to a gun barrel with the bore of the barrel in alignment with the seal port, and a condenser comprising a metal shield secured to the forward part of the body and having a part extending rearwardly and open at its rear end, said part 25 surrounding the discharge ports and baffle ports, and a part projecting forwardly beyond the seal port and having its forward end open.

4. A recoil controlling device comprising a metal body having a combustion chamber therein, said body having at its forward end a seal port and a reaction shoulder surrounding the inner end of said port, and having discharge ports extending outwardly and rearwardly from said shoulder and baffle ports in its side wall 30 at the rear of the discharge ports, and also having means at its rear end for connecting the device to a gun barrel with the bore of the barrel in alignment with the seal port, and a condenser comprising a metal shield secured to the forward part of the body and having a part extending rearwardly and open at its rear end, said part 35 surrounding the discharge ports and baffle ports, and a part projecting forwardly beyond the seal port and having its forward end open.

ROBERT H. S. HUGHES.
